UNITED STATES PATENT OFFICE.

ALBERT F. PRESTON, OF BOSTON, MASSACHUSETTS.

BINDING-MACHINE.

1,186,127.

Specification of Letters Patent.

Patented June 6, 1916.

Application filed May 1, 1915. Serial No. 25,329.

To all whom it may concern:

Be it known that I, ALBERT F. PRESTON, a citizen of the United States, residing at Boston, county of Suffolk, State of Massachusetts, have invented an Improvement in Binding-Machines, of which the following description, in connection with the accompanying drawing, is a specification, like characters on the drawing representing like parts.

This invention relates to improvements in binding machines.

Boot, shoe, garment and other patterns or sheet forms of card board, paste board, compressed fibrous materials and compositions having similar properties, are used in cutting out desired shapes and sizes of different materials. The pattern is superposed upon the material and the operative then passes a knife or other cutting instrument around the edges of the pattern thus cutting out of the material one or more articles of the pattern shape. It is essential to the continued use of such patterns that their edges be reinforced and protected against natural wear and against injury by careless cutters. Metallic binding applied to the pattern edges efficiently protects and coincidentally insures greater ease and accuracy in cutting. The binding employed, as sold to the trade, is in the form of U-shaped or flanged strips of flexible sheet metal and is adapted to cover the pattern edge, its flanges overlapping the adjoining portions of the adjacent pattern faces. This binding is usually applied as one continuous strip running around the pattern rather than being applied in sections. This continuous binding is applied to the pattern edge and pressed thereon. It is necessary to bend the binding in order to secure it to corners of patterns and, in order to insure the fit of the binding to a corner edge and to insure a symmetrically protected corner, it is essential to remove a small portion of the binding—to cut a notch therein. Unless the notch is made at the exact point, an ill-fitted corner results detracting from the value of the pattern, if not entirely destroying its utility. Practice has shown that if a portion of the binding flange is not removed a roughened or burred corner will result. This defect is most effectively overcome by cutting out a triangular piece of metal from the flanges of the binding strip, the apex of the cut being opposite the apex of the angle of the pattern. To accom-

plish this accurately it is necessary that the point, at which the flanges of the binding strip are to be cut, be determined when the binding strip is adjacent the pattern edge and that the flanges be cut when separated from the pattern.

The object of this invention is to provide a high-speed power binding machine for affixing protective binding to pattern edges.

Another object is to provide a binding machine with a rapidly functioning cutting means by which notches can be expeditiously made in the pattern binding.

Another object is to provide means to insure the notching of the binding at any predetermined point therein.

It is a further object to provide a machine wherein the pattern and partially attached strip may be positioned at a notching gage when the strip is held adjacent the pattern edge corner and the notch may be cut at the point indicated by the gage when the binding is separated from the pattern.

In order to afford an understanding of this invention, a selected embodiment has been illustrated in the accompanying drawings and will now be described.

Figure 1 is a side elevation of the binding machine; Fig. 2 is an end elevation partially broken away to show the drive; Fig. 3 is a plan of the notching and gaging mechanism; Fig. 4 is a front elevation partially broken away to show the means of actuation of the cutter; Fig. 5 is a plan view showing the parts in position ready for the cutter to be operated; Fig. 6 is a view of the notching mechanism looking from the inside; Fig. 7 is an underside view of the notching mechanism; Fig. 8 is a perspective view of the end of the finger which receives the binding; Fig. 9 is a perspective view of the die plate; Fig. 10 is a perspective view of the cutter; Fig. 11 is a view looking at the end of the cutter driving mechanism showing the shaft and the eccentric stud with roll mounted on it; Fig. 12 is a perspective view of a modified form of the clamp; Fig. 13 is a section on the line 13—13, Fig. 1, showing the feed and pressure rolls; Fig. 14 is a section on the line 14—14, Fig. 1; Fig. 15 is a plan of a modified form of rolls; Fig. 16 is a detailed section of a novel binding strip.

In this selected embodiment, the power binding machine has a base 1 secured to a suitable support such as a bench 2. The

frame 3 which comprehends the gear and shaft housing 4, at the driving or power end, has four laterally projecting arms which terminate respectively, at the work 5 end of the frame, in the cutting apparatus, the upper feed and pressure roller, the lower feed and pressure roller and the means for elevating the lower roller. Power is transmitted to the machine by a belt (not shown) 10 which engages step pulley 5 secured by a set screw 6 to the end of the power shaft 7 which has its bearing in the frame. The speed of the main shaft 7 is varied by means of shifting the belt on various steps of the 15 pulley, and for that purpose any type of belt shifter may be employed. The main shaft has integral therewith a worm 8 which engages a gear 9 fastened to the upper feed and pressure shaft 10. Mounted upon this 20 shaft 10 and revoluble therewith is the smaller gear 11 which meshes with the twin gear 12 mounted upon the lower feed and pressure shaft 13, so that these two shafts, which carry at their work ends the upper 25 and lower feed and pressure rollers, respectively, will be revolvably actuated in opposite directions, at the same rate of speed and will thus feed forward a pattern placed therebetween.

30 The uppermost or cutter shaft 14 has mounted thereon at its rear end a pinion 15, shown in dotted lines in Fig. 2, which meshes with the gear 16 mounted on a stud shaft 17. The cutter shaft 14 terminates at 35 its power end in an end bearing cap 18. The pinion 19 is concentrically superposed on the gear 16 and secured to the stud shaft 17. This pinion meshes with the gear 11. The cutter shaft 14 is thus rotated at a higher 40 rate of speed than that of the feed rolls—in practice, the speed ratio of approximately five and one-half to one has been found efficient. The gear 9, secured to the shaft 10 by a suitable set screw shown in Fig. 1, has 45 countersunk on its rear face a steel bearing plate 21 which offers a bearing to the power ends of the shafts 13 and 14 and the cap 18 of the cutter shaft—thus preventing any possible lateral thrust. The three shafts are 50 suitably journaled and supported in the frame and frame arms.

The upper feed and pressure shaft 10, at 55 its work end, extends through the casing arm and carries keyed thereto the upper feed and pressure roller 22, and the retaining screw 23. The lower feed and pressure shaft 13 has a similar roller 24. The peripheries of these twin rollers 22 and 24 are beveled so that the greatest diameters are opposed and 60 are somewhat back of their front faces.

The frame casing carrying the lower feed and pressure shaft 13 at the work end is reduced and has slidably mounted thereon a sleeve 25 to which is secured a handle for 65 pushing the same inwardly against the ac-

tion of the washer spring 26. This sleeve is secured against rotation by means of a lug projecting from the casing and engaging a guideway in the sleeve. The sleeve 27, also mounted on the reduced casing arm and 70 carrying at its front end and next to the lower feed and pressure roller the different sized rear positioning rollers and the fin back guide 28, is adjacent the sleeve 25 and normally bears thereagainst. This roller 75 sleeve is secured against rotation by means of a lug on the rear sleeve, which is adapted selectively to engage slots or guideways 29 in the roller sleeve, a slot being opposite each roller and the fin 28.

It is necessary to remove the pattern and binding from the work rolls to cut a notch in the binding when an angle is encountered in rolling and pressing on the binding strip. The facile disengagement of the pattern and 80 partially attached binding is effected without stopping the machine by means which cause the separation of the two feed and pressure rollers. This is the function of the mechanism carried by the lowest arm of the frame which effectuates the elevation and depression of the lower feed and pressure roller 24 into and out of operating position with relation to the twin roller 22. The casing arm has an end opening for the 85 lower feed and pressure shaft 13 whereby this shaft may be moved in the vertical plane of its axis thus permitting the two rollers to be moved apart while the machine is running. A vertically adjustable bearing is 90 provided for the shaft 13. It comprises a cylindrical guide 30 which has a transverse central boring forming the shaft bearing and a threaded reduced portion or stem 32 adapted to be received within an interiorly 95 threaded cylindrical nut 33. The guide 30 and its engaging nut 33 are slidably positioned in the vertical way 31, shown in dotted lines in Fig. 1, which extends through the frame arm containing the lower roller 100 shaft 13 and the lowest frame arm. The nut, preferably closed at its bottom face, rests upon the stud shaft 34 which has a portion of its periphery beveled away, forming 105 a flat surface 35. The function of this 110 flat surface is to provide means whereby, upon the rotation of the stud shaft, the nut, and therefore the guide 30, may be cammed into elevated or depressed position accordingly as the periphery or the flat surface of 115 this shaft is presented to the nut through manual rotation of the stud shaft by means of a bar lever 36 secured therein. A limited path is provided for the lever 36 by an elongated opening 37 cut in opposed sides of the 120 lowest frame arm. A weighted head 38, shown as a ball, is affixed to the lever end so to retain the shaft that its periphery is presented to the nut. The lower roller shaft 13 is thus normally elevated and the lower 125 130

roller held in effective operating position with relation to the upper roller. The rollers drop apart when the head is raised.

The cylinder nut 33 is provided with a plurality of apertures 39 in which a small pin lever 40 is adapted selectively to be inserted. Graduated adjustment of the nut on the threaded stem 32 is effectuated through rotation of the nut by means of this lever 40. The operating space between the lower and upper rollers thus may be adjustably varied for different thicknesses of patterns or binding strips.

It is necessary, in order to preserve the contour of the pattern corners and to obtain a smooth edge, to cut a small miter or notch in the flanges of the U-shaped binding strip. Practice has demonstrated that the most symmetrically bound and therefore the most efficiently protected corner is one where the apex of the flange notch is exactly opposite the apex of the pattern angle. This result is accurately accomplished by holding the partially attached binding strip against the pattern edge up to the corner, then by positioning a gage in the flanged strip at the apex of the angled pattern corner, whereby the point at which the apex of the notch to be cut in the flanges of the strip may be indicated with precision on the strip, and, finally, by moving the binding strip, partially attached to the pattern, while retentively held with relation to the gage, to the cutting element whence the notch is unerringly cut. Such is the function of the cutting or notching member secured to the work end of the topmost shaft which consists primarily of the cutting means and the mechanism for correctly positioning the binding strip.

The topmost or cutter shaft arm of the frame has, at its work end, a reduced portion 43 and mounted thereon is the collar 44 which is centrally bored to fit the reduction and is adjustably secured against movement thereon by means of the set screw 45, shown in dotted lines in Fig. 11. The collar 44 has a pair of threaded holes 46 therein, which are adapted to receive in threaded engagement suitable screws 47, inserted through the holes 48 in the block 49, by which means the block 49, bearing the notching means, is secured to the collar and thus is carried by the uppermost frame arm.

The block 49 has a vertical slot 50 in which are positioned the die 51 and the cutter 52. The die is secured against movement in the vertical slot by means of the set screw 53. The rear face of the die, which as shown is flush with the surface of the block, also impinges against the end face of the reduced portion of the frame arm and collar 44. The die 51 has a bearing face 54 which has a circular hole 55 therein. The cutter shaft 14, at the work end, has a reduced portion

56 which is adapted to fit into the hole 55 and to rotate freely therein. The cutter 52 is slidably secured against the bearing face 54 of the die and is adapted to reciprocate vertically thereon. Reciprocatory movement is imparted to the cutter by means of the eccentric stud 57 on the end of the reduced portion 56 of the cutter shaft. This stud bears on its periphery a roller 58 which is adapted to reciprocate transversely in the lateral slot 59 which is cut in the face of the cutter 52 and is of a width but slightly greater than the diameter of the external edge of the roller 58. Thus, the rotary motion of the shaft 14, through the medium of the eccentricity of the stud, its roller and the lateral slot, is translated into the vertically reciprocatory motion of the cutter.

The bearing face 54 of the die bears a flange 60 which forms a lateral bearing guide for the reciprocating cutter 52. The flange, opposite the hole 55, is arcuately cut away at 61 to allow full play to the eccentric stud roller in its traverse of the slot 59. The edge of the cutter, normally adjacent this flange, is partially beveled away, leaving a double-edged tooth 62—substantially of a triangular configuration. The die, at its upper end, has an opening cut through both its flange and face, forming pairs of shearing edges to coöperate with the cutting edges of the double-edged tooth. The edge 63 of the die flange and the edge 64 of the die form shearing edges for the lower cutting edges of the triangular tooth; while, the upper edge 65 of the flange cut and the upper edge 66 of the die form shearing edges coöperating with the upper edges of the tooth. This opening in the die and flange is made at an angle to the flange 60 and forms, through the die, a beveled or sloping channel 67, as shown in dotted lines in Fig. 9, providing a guideway for the flanged binding strip. The die flange 60 is cut away at 68 and, coöperating with the beveled portion 69 of the cutter, forms a way by which means pieces of metal cut from the flanges of the binding strip on the downward stroke of the cutter may fall into the channel 99 of the block 49 and drop away. Lateral movement of the cutter is prevented by the flange 60 of the die and it is held thereagainst and wear taken up by means of the screw 70 inserted in a threaded aperture in the side of the block 49 and adjustably locked by the nut 71. A similar screw 72, adapted to be adjustably locked by the nut 73, is inserted in a threaded aperture cut through the block 49 to the vertical slot 50, and, bearing against the cutter's rear face, positions it against the bearing face of the die and similarly may be changed to take up wear. The width of the tooth 62 is such that, when midway its stroke, it will be positioned in the center of the opening formed by the trans-

verse cut made through the die 54 and its flange 60, and space at such position is afforded for the two flanges of the U-shaped binding strip to pass the one above the 5 tooth and the other below. Further, the vertical movement of the tooth is so limited that it is impossible for the tooth to slide above or below the channel, leaving it completely open, and hence, the metal binding can only enter the path of the tooth when 10 the tooth is midway and the flanges of the binding are placed on either side thereof—in effective operating or cutting position.

A gaging and movable positioning apparatus for the flanged binding strip is provided. This apparatus operates in such way as to assure the cutting of the notch in the binding so that the apex of the triangular cut will be precisely opposite the apex of 20 the pattern angle. In binding a pattern, the operative usually starts binding along a straight edge. The pattern is removed from the feed and pressure rollers when a corner is approached and, with its partially attached binding, is elevated to this apparatus supported on the frame side of the block 49. The binding is placed within a clamping member and the pattern angle or corner is positioned with relation to the 30 gage and the binding then clamped. The clamping member which is slidably mounted, is then moved so that the binding flanges are presented to the notching means and are cut at such predetermined point with the result that a perfect, symmetrically bound edge 35 must ensue when the strip is thereafter returned to the rollers and rolled on the pattern edge. At the time of notching, the pattern is separated from the binding so that 40 injury to the pattern corner is impossible and interference by it with the accurate notching and positioning of the apex of the notch avoided. It is thus seen that the apex of the triangular notch to be cut is determined 45 while the binding is held against the pattern edge and that, in cutting the notch at the predetermined point, the pattern is separated from the binding.

A support 74 is secured to the block 49 by 50 means of the screws 75. A slide 76 is adapted to reciprocate in a runway formed in this support and is retained therein by means of the overhanging flange 77. The reciprocatory motion of the slide is limited by means 55 of the pins 78 which are adapted to slide into and out of engagement with the slots 79 cut in the bottom of each end of the support. A trough 80 is mounted upon the slide 76 at an angle. This trough is preferably 60 integral with the slide and moves therewith. The arm 81, which forms one member of the clamp, has two preferably integral base plates 82 and 83 which are adapted to reciprocally slide in the trough. The motion 65 of the base plates and hence of the arm 81 is

limited by means of a detent 84 comprising a rectangular piece of metal secured at the substantially midway point of the trough. The arm 81 and its preferably integral base plates 82 and 83, are slidably secured to the 70 trough by means of the angled strap 85 fastened by the screws 86 to the side of the arm and having its angled portion 87 impinging upon the underside of the trough. The edge 88 of this strap portion 87 is cut away to allow full play to the sliding arm 81 in its forward movement above the trough. 75

The rear base plate 82, integral with the sliding arm 81, has a pin 89 on which is pivotally mounted the co-operating clamping 80 member 90, shown in Fig. 8. This clamp 90 has a hole adapted to receive the pivot pin 89. The forward end of this clamp bears a projecting finger 91, the tip of which is beveled and functions as the gage 92. 85 Grooves 93 are cut in the inner face of the clamp, one on each side of the finger, and are adapted to receive therein the flanges of the U-shaped binding strip when it is positioned in the clamping and gaging means. 90 These grooves 93 extend only a portion of the way back on the clamp as the inner clamp face is cut away with the result that the clamping function is attained between the forward portions of the arm 81 and the 95 clamp.

The arm 81, at its forward end, has a reduced portion or tip 94 which is of a height slightly greater than the finger 91. The end portion of the finger is adapted to impinge 100 against the tip 94 substantially along the middle thereof, the gage 92 and the tip end coincidentally terminating. The side of the clamp 90 opposite the finger has a reduced portion 95 which insures clearance of the 105 back of the die by the clamp in its rearward movement. The end face of the arm 81 adjacent the reduced portion or tip thereon and the similar end face 96 of the clamp are 110 cut off at an angle to their longitudinal axes in order that, when the arm and clamp are withdrawn to rearward position and the slide moved to its inner position, the ends of the arm and clamp may slide past the rear face of the die. The width of the tip 115 94 is smaller than the flange opening of the die 51 and hence, when the slide and arm are fully retracted, the arm tip 94 and finger 91 may pass within the opening and the flanges of the binding strip retained in the 120 clamp may be presented to the path of the cutting tooth 62, as shown in Fig. 5.

The modification shown in Fig. 12 is of a clamping member 97 which is employed in place of the clamp 90. This member 97 is 125 similar to the clamp 90 but is without the projecting finger, gage and grooves, and functions solely as a clamping member. When the clamp 90 is used, the edge of the pattern 98 (shown in dotted lines in Fig. 3) 130

is held against the binding strip between its flanges and the pattern is pushed inwardly until it touches the gage 92 and the binding is then clamped. But, when employing this 5 modification 97, the operative simply slides the binding strip between the clamping members, positions the angle of the corner of the attached pattern opposite the end 94 of the arm 81, clamps the binding in such 10 position and thence proceeds with the notching. Thus, it is evident that, in using the modified clamp, the operative relies upon his eye to position correctly the binding strip in the clamping member. 15 The operation of this machine is simple, rapid and efficient and does not require the services of a skilled operative. In binding a pattern, the operative holds the binding strip on the pattern edge, raises the lever 36, 20 which through the agency of the adjustable bearing means depresses the lower roller, the pattern edge and binding are held between the rollers, and the lever is depressed and the lower roller is elevated to effective 25 operating distance from the upper. The pattern is then automatically fed between the rollers, due to the fact that they are rotating in opposite directions, and the binding is pressed thereon. When a corner is 30 approached the operative raises the lever 36, the lower roller is depressed, and facile disengagement of the pattern is permitted. The operative removes the pattern to notch the flanges opposite the corner. The free 35 end of the partially attached binding strip is then presented to the gaging device. The flanges of the strip are placed in the grooves 93, the gage 92 entering within the channel of the strip. The binding with the pattern 40 held thereagainst is slid inwardly until the apex of the pattern corner angle comes to rest against the gage formed by the beveled end of the finger. The gage thus indicates the precise point, where the apex of the 45 binding notch should be, in order that such apex may be opposite that of the pattern corner angle. Such position is shown in Fig. 3. The operative then grasps the arm and clamp which causes the binding strip 50 to be positively retained in such position. The arm and clamp composing the clamping member are pulled to rearward position while the slide is pulled to inner position when the pattern will be separated from the 55 binding strip by the die and cutter and the flanges of the binding strip will be presented to the path of cutting teeth. Such position is shown in Fig. 5. The slide and the clamping member are both immediately returned 60 to normal position, the clamp released and the pattern removed. The binding having thus been notched, the pattern is again placed between the feed and pressure rollers, and the pattern and binding are again 65 automatically fed therebetween and the

binding pinched on the pattern. In pinching on the binding strip at the corners it frequently occurs that the rollers run across the adjoining pattern edge to which the strip has already been affixed. In such case 70 a groove is pressed by the beveled peripheries of such rollers as those to which reference has been made. Further, with strips of certain metals, slightly rounded top and bottom faces of the strip result. Such defect 75 may be overcome by clamping the substantially flat rollers shown in Fig. 15. These rollers are illustrated as beveled each way from their opposed lines of greatest diameter about three degrees from the horizontal. 80 However, rollers having horizontal or flat peripheries may be employed. A binding strip which may effectively be employed with the flat and substantially flat rollers is shown in enlarged sectional detail in Fig. 85 16. This strip has outwardly flaring side walls 100 and each carries longitudinally its length a hair-line rib 101. This rib is formed, in this selected embodiment, by turning in the edge of the binding strip 90 substantially one one-thousandth of an inch. When pressed upon the pattern edge by the flat or substantially flat rollers, the rib is embedded in the pattern both top and bottom. A pattern thus bound, not only will 95 have a more retentively affixed reinforcement but will lie flat upon the material to be cut.

Having fully described my invention, what I claim as new and desire to secure by 100 Letters Patent is:

1. In a binding notching means, relatively movable cutting members coöoperating to notch the flanges of a binding strip and means movable to direct the binding to the 105 path of the cutting members, the movement of the last-mentioned means being limited whereby a notch may be cut in the binding flanges at a predetermined point.

2. In a binding notching means, relatively 110 movable cutting members coöoperating to notch the flanges of a binding strip, a movable means adapted to direct the binding to the path of the cutting members and means for securing the binding to said movable 115 means whereby said binding may be moved to the cutting members and a notch cut in said flanges.

3. In a binding notching means, relatively movable cutting members coöoperating 120 to notch the flanges of a binding strip and means movable with the binding strip to position the binding to the path of the cutting members whereby a notch may be cut in the binding flanges at a predetermined 125 point.

4. In a binding notching means, a cutting element, a relatively movable cutting element coöoperating therewith to notch the flanges of a binding strip and means mov- 130

able with the binding strip to position the binding to the path of the cutting member and means for retaining said binding strip in said movable means whereby a notch may 5 be cut in the binding flanges at a predetermined point.

5. In a binding notching means, a cutting element, a relatively movable cutting member coöperating therewith to notch the 10 flanges of a binding strip and a carrier adapted to position the binding to the path of the cutting member, a pivoted clamp for retaining said binding strip in said carrier whereby a notch may be cut in the binding 15 flanges at a predetermined point.

6. In a binding notching means, a cutting element, a relatively movable cutting member coöperating therewith to notch the flanges of a binding strip, a guideway 20 formed adjacent said element, means slidably mounted in said guideway adapted to direct the binding to the path of said cutting member whereby a notch may be cut in the binding flanges at a predetermined point.

25 7. In a binding notching means, a cutting element, a relatively movable cutting member coöperating therewith to notch the flanges of a binding strip, a slide mounted adjacent said element and adapted to carry 30 said binding strip, means for limiting the inward travel of the slide to said element whereby when the carrier is so limited the flanges of said strip will be positioned in the path of the cutting element and a notch cut 35 at a predetermined point.

40 8. In a binding notching means, a cutting element, a relatively movable cutting member coöperating therewith, to notch the flanges of a binding strip, a carrier slidably mounted adjacent said element and adapted 45 to carry said binding strip, means for limiting the outward travel of said carrier whereby said carrier is prevented from being demounted and is positioned to receive the flanged binding strip.

50 9. In a binding machine, notching means, movable means for guiding a flanged binding strip to said notching means, detents adapted to limit the outer and inner travel of said guiding means, whereby when said movable means is extended the binding strip may be placed in said movable means and when retracted said strip is presented to the notching means.

55 10. In a binding notching machine, means for notching the flanges of a binding strip, a slide adapted to reciprocate to and from said notching means, an arm on said slide adapted to reciprocate therewith whereby a flanged 60 binding strip may be guided to the notching means and a notch cut in the flanges.

65 11. In a binding notching machine, notching means, a slide adapted to reciprocate to and from said notching means, an arm secured to said slide at an angle to its longi-

tudinal axis, said arm being adapted to reciprocate therewith whereby a flanged binding strip may be guided to the notching means and its flanges notched.

70 12. In a binding notching machine, notching means, a support for said notching means, a slide adapted to reciprocate on said support, an arm on said slide at an angle to its longitudinal axis, said arm being adapted to reciprocate therewith, a clamping member adapted to retain a flanged binding strip against said arm whereby said binding strip may be guided to and removed from the notching means and its flanges notched at a predetermined point.

75 13. In a binding notching machine, notching means, a support for said notching means, a slide adapted to reciprocate on said support, an arm on said slide and movable therewith, a clamping member pivotally secured to said arm and movable therewith and adapted to coöperate with said arm to retain a flanged binding strip whereby said binding strip may be guided to and from 80 said notching means and a notch cut in said flanges at a predetermined point.

85 14. In a binding notching machine, notching means, means movable with a flanged binding strip to present the binding to the path of said binding notching means whereby the flanges may be cut and means on said movable means for gaging the point on said binding where such cut will be made.

90 15. In a binding notching machine, notching means, a slide adapted to reciprocate to 100 and from said notching means, an arm on said slide and movable therewith, a clamping member on said slide adapted to coöperate with said arm to retain on said slide a flanged binding strip, a finger on said clamping member whereby the point may be determined at which a notch will be cut in said flanges upon movement of said slide to said notching means.

105 16. In a binding notching machine, notching means, binding strip engaging means and means for moving said binding strip engaging means longitudinally and laterally to position a predetermined portion of the binding strip in the path of said notching means.

110 17. In a binding notching machine, notching means, a slide reciprocally mounted adjacent said means, a clamp reciprocally mounted upon said slide whereby a flanged binding strip may be positioned in said clamp when said slide and said clamp are at their outer and forward positions respectively and when drawn to their respective inner and rearward positions said flanges are presented to the path of the notching means.

120 18. In a binding notching machine, notching means, a member adapted to reciprocate adjacent said means, a clamping means re- 125

ciprocally mounted upon said member and comprising an arm, a clamp pivotally mounted on the arm and a gage, whereby a flanged binding strip may be inserted and held in said clamping means, said member and said clamping means coöperatively reciprocated, and the flanges of the binding strip presented to said notching means and a notch cut in said flanges at the point indicated by said gage.

19. In a binding notching machine, notching means, a member adapted to reciprocate adjacent said means, clamping members reciprocally mounted upon said member, a finger on one of said members and projecting therefrom, grooves on said finger-bearing member on each side of said finger, adapted to receive said strip flanges, the end of said finger, upon movement of said reciprocating member and said clamping means, being adapted to be positioned adjacent the notching means whereby said flanged strip may be retentively positioned in said clamping means and carried to the notching means and the flanges there cut at a predetermined point.

20. In a binding notching machine, notching means, a movable member adapted to direct a flanged binding strip to said notching means, means movable with relation to said movable member, a finger carried by said movable means and adapted to be inserted between the flanges of said strip, a gage on said finger adapted to indicate on said strip where a notch will be cut in the flanges when, through the coöperation of said movable member and means, said strip is presented to the path of the notching means.

21. In a binding notching machine, notching means, a member adapted to reciprocate adjacent said notching means, an element adapted to reciprocate on said member, the path of reciprocation of said element being at an angle to the path of reciprocation of the member, a finger on said element adapted to be inserted between the flanges of a flanged binding strip, a gage on said finger adapted to have positioned thereagainst the corner of a pattern partially attached to said binding strip, whereby, upon coöoperative movement of said member and said element, said flanges will be presented to the notching means and a notch cut therein as indicated by said gage.

22. In a binding notching machine, notching means, a member adapted to reciprocate adjacent said notching means, a clamp adapted to reciprocate on said member, the path of reciprocation of said clamp being at an angle to the path of reciprocation of the member, said clamp comprising an arm, a clamping member pivotally secured thereto, said clamp being adapted to receive and retain a flanged binding strip, whereby

when said member and said clamp are co-operatively reciprocated, said strip may be clamped and carried to said notching means and a notch cut in the flanges thereof.

23. In a binding notching machine, notching means comprising a die and a cutter, said die having an opening leading to the path of the cutter, and movable means adjacent said notching means and adapted to enter said opening and direct a flanged binding strip to said cutter whereby the flanges of said strip will be notched.

24. In a binding notching machine, notching means comprising a die and a cutter, said die having an opening leading to the path of the cutter, a clamp reciprocally mounted, having reduced end portions and adapted to receive a flanged binding strip whereby, upon reciprocation of said clamp, the reduced end portions may enter said opening and direct the binding strip flanges to the path of the cutter.

25. In a binding notching machine, notching means, a slide mounted adjacent to said notching means and having detents for limiting the forward and backward movement thereof, a clamp slidably mounted upon said slide in angular relation thereto, and a detent for limiting the longitudinal movement of said clamp whereby said clamp may be extended to engage a binding strip and retract it whereby said detents will cooperate to position said clamp to receive a flanged binding strip and also to position said binding strip flanges in the path of the notching means.

26. In a binding notching machine, a vertically reciprocating cutter, a horizontally reciprocating slide mounted adjacent to said cutter, an angularly disposed clamp horizontally reciprocal on said slide, whereby the resultant movement of said slide and said clamp will position a predetermined portion of a flanged binding strip in the path of said cutter.

27. In a binding notching machine, notching means, a movable binding strip engaging means adapted when extended to abut against a pattern and to engage the binding strip immediately adjacent thereto and adapted to be retracted to separate the binding strip from the pattern and to position the same in the path of the notching means.

28. In a pattern binding machine of the character described including a driving element, a frame, shafts revoluble in said frame, opposed and oppositely actuated rollers on two adjacent shafts whereby a pattern and binding strip may be passed between said rollers and the strip pressed on the pattern edge, and means for manually elevating and depressing one of said adjacent shafts comprising a bearing, a rotatable member having threaded engage-

ment with said bearing whereby upon rotation of said member, said bearing may be elevated or depressed.

29. In a pattern binding machine of the character described including a driving element, a frame, a pair of adjacent and oppositely actuated shafts revolubly mounted in said frame, a movable bearing for one of said shafts, said bearing having a threaded reduced portion, a nut adapted to engage said reduced portion, means for selectively engaging portions of said nut whereby upon its rotation said bearing will be elevated or depressed.
- 15 30. In a pattern binding machine of the character described including a driving element, shafts driven thereby, opposed and oppositely actuated rollers on adjacent shafts whereby a pattern and binding strip 29 may be passed between said rollers and the strip pressed on the pattern edge, means operable to move the rollers into and out of

working position and means adjustable to regulate the spaced relation of the rollers in working position.

25

31. In a pattern binding machine of the character described including a driving element, shafts driven thereby, opposed and oppositely actuated rollers on adjacent shafts whereby a pattern and binding strip 30 may be pressed between said rollers and the strip pressed on the pattern edge, a movable bearing for one of the roller-bearing shafts, a member having threaded engagement with said bearing, means for adjusting said member whereby regulation of the spaced relation of the rollers is obtained under all working conditions and means operable to move the rollers into and out of working position.

35

40 In testimony whereof, I have signed my name to this specification.

ALBERT F. PRESTON.
